DEFENSIVE PUBLICATION

UNITED STATES PATENT OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection, and reproduction may be purchased for 30 cents a sheet.

Defensive Publication applications have not been examined as to the merits of alleged invention. The Patent Office makes no assertion as to the novelty of the disclosed subject matter.

Robert W. Alexander, Jr., Los Gatos, John M. Bell and John A. Christensen, San Jose, Roger W. Harvey, Santa Cruz, Katherine A. Hitchcock, Atherton, Robert W. Martin, San Jose, and Alice K. McMullen, Campbell, Calif., assignors to International Business Machines Corporation, Armonk, N.Y.

Continuation of application Ser. No. 327,252, Jan. 26, 1973, which is a continuation of application Ser. No. 150,853, June 7, 1971. This application Sept. 17, 1973, Ser. No. 398,140

Int. Cl. G06f 9/12

U.S. Cl. 444—1

51 Sheets Drawing, 284 Pages Specification

A file structure for an on-line system. A central processing system having core and direct access storage devices and input/output terminals is programmed for on-line applications such as inventory control, manufacturing process control, library management. The file structure for those applications includes an item detail file including a logical record for each individual item in the inventory, an access point file including inverted lists of item details having search or control significance, a code translation file having alphabetic translations of coded data in the other files. Also included may be a print queue/verification file and date control file. Each file includes one or more index and data files. Forward and reverse indexing connects the files through use of implicit pointers and item numbers. On-line updating of record detail is simultaneously performable with review of that record. Events having future significance are triggered automatically. Logical and physical overflow records are accommodated, as are variable length logical records built on variable length counters. Last-in/last-out updating of logical record lists together with reverse order data fields and length/sequence fields optimizes "get" time. The application functions include ordering, receiving, cataloging, circulating, searching, and file maintaining.
